UNITED STATES PATENT OFFICE.

CARL G. HEIBY, JOHN BURKAM, DAVID E. LINDQUIST, FRED L. RIGGIN, EBENEZER W. ALLEN, AND RICHARD LAU, OF SARNIA, CANADA, ASSIGNEES, BY MESNE ASSIGNMENTS, TO MUELLER METALS COMPANY, OF PORT HURON, MICHIGAN, A CORPORATION OF MICHIGAN.

PRIMER FOR SHELLS.

1,331,922.

Specification of Letters Patent. Patented Feb. 24, 1920.

Application filed January 17, 1918. Serial No. 212,232.

To all whom it may concern:

Be it known that we, CARL G. HEIBY, JOHN BURKAM, DAVID E. LINDQUIST, FRED L. RIGGIN, EBENEZER W. ALLEN, and RICHARD LAU, all citizens of the United States, except ALLEN, a subject of Great Britain, residing at Sarnia, in the county of Lambton and Dominion of Canada, have invented new and useful Improvements in 10 Primers for Shells, of which the following is a specification.

The present invention relates to primers for shells, and has for its object to produce a forging suitable for such primers from a blank or slug, which forging, after its has passed through the die press, and has been trimmed, will be of such form that the work of finishing the primer by machining, threading and boring will be reduced to a 15 minimum, the forging as it comes from the press being substantially in final form with merely sufficient metal to allow for the finishing operations, there being practically no surplus metal to be cut away aside from 20 such metal as is removed during machining, threading and boring the several sections of the primer which have to be so treated.

In order that the invention may be understood by those skilled in the art, we have 25 shown herein a primer for shells constructed in accordance with the invention, and in the drawings—

Figure 1 is a view in side elevation of a blank or slug from which the primer is made.

Fig. 2 is a view in section of the slug after it has been forged and prior to trimming.

Fig. 3 is a view in section of the forging after trimming.

Fig. 4 is a view in section of the finished primer.

Referring to the drawings by numbers, like numbers indicating like parts in the several views, the slug 10, shown in the present instance as cylindrical, may be formed in any suitable manner, as by casting as an individual slug, by casting in a long bar from which the slugs may be cut, or by cutting the slugs from a rolled or drawn bar, the 45 manner of forming the slug being immaterial for the purposes of the present invention. The slug shown in Fig. 1 is indicated as an individually cast slug, and where these

slugs are cast individually there is ordinarily a top or crown 11 which contains 55 more or less dross or floating impurities which rise to the top of the molten metal, and form an incrustation of impure matter. This will first be machined off down to the dotted line 12, leaving a section of pure 60 metal to be subjected to the action of the press. The machined slug will have formed therein, generally, although not necessarily, in the center of one of its ends, a depression or cavity 13 which is designed to engage a 65 complementary part on a die member so as to center the slug accurately between the dies, these dies not being shown in connection with the present development, as they may be of any desired or necessary form, dependent, of course, on the article to be produced.

The blank after it has been subjected to the action of the dies is in the form shown in Fig. 2, having the annular upstanding top 75 14 centrally of which is a projecting part 15, and below said annular top 14 are the stepped cylindrical sections 16 and 17. At the base of the bottom section 17 is a laterally projecting annular fin or flash 18, where 80 the slight excess of metal is squeezed out by the dies, and this annular flash 18 will afterward be trimmed off, bringing the forging to the condition shown in Fig. 3, where it is ready for finishing.

The finished primer is shown in Fig. 4, and it will be observed that the annular top 19 is of substantially the forged form shown at 14 in Fig. 3, there having been provided merely sufficient metal to permit of a good 90 finishing by machining, but without compelling the removal of any great quantity of metal by the relatively slow and costly method of machining. The same is true with respect to the threaded section 20, 95 which is formed upon the forged section 16, which forged section provides merely a sufficient amount of metal to permit a proper threading operation. The base portion 17 of the forging is machined away, as shown 100 at Fig. 4, to a slight extent to give the annular rim or rabbet 21. It will be apparent that the finished primer shown in Fig. 4 is exteriorly of substantially the form of the forging of Fig. 3, except with respect to the 105 finishing operations, there being compara-

tively no loss of metal or expenditure of time and labor by the machining operations, which are resorted to merely to give the proper finish and threading to the pre-formed article.

The same is true with respect to the interior borings and cavities, for the top recess 22 of the shell is merely finished so far as its annular wall is concerned, and slightly 10 deepened as shown in Fig. 4, so as to give greater projection to the central boss of the forging. The central boss and the body of the primer are then bored to form the central chamber 23, a portion 24 of which is 15 threaded as shown.

By this method an article of this character may be expeditiously formed, and at comparatively slight cost, owing to the fact that the costly steps of machining to bring 20 the blank or slug to its finished form are practically eliminated.

We claim:—

1. A forging for shell primers having a body portion with an annular cavity forged 25 in one end thereof, centrally of which is forged a projection.
2. A forging for shell primers having a body portion, the exterior surface of which is stepped to form projections for machining and threading, and in one end of which

is forged a cavity with a centrally disposed projection.

3. A forging for shell primers comprising a body portion having an annular upstanding rim within the cavity of which is 35 a centrally disposed forged projection, a stepped surface of larger diameter adjacent said annular rim to provide a threading element, and a base portion of enlarged diameter to provide the material for rabbeting. 40

4. A forging for shell primers having a body portion, the external surface of which is stepped to form projections for machining and threading, and in one end of which is forged a cavity. 45

5. A forging for shell primers comprising a body portion having an annular upstanding rim, a stepped surface of larger diameter adjacent said annular rim to provide a threading element and a base portion of enlarged diameter to provide the material for rabbeting. 50

In testimony whereof we have hereunto set our hands.
